UNITED STATES PATENT OFFICE.

SIDNEY W. FLETCHER, OF VIBORG, SOUTH DAKOTA.

KITE ATTACHMENT.

SPECIFICATION forming part of Letters Patent No. 692,998, dated February 11, 1902.

Application filed March 19, 1901. Serial No. 51,903. (No model.)

To all whom it may concern:

Be it known that I, SIDNEY W. FLETCHER, a citizen of the United States, residing at Viborg, in the county of Turner and State of 5 South Dakota, have invented a new and useful Kite Attachment, of which the following is a specification.

This invention relates to kites, and more particularly to attachments therefor; and the 10 object of the invention is to provide a construction wherein a parachute may be attached to the kite in such manner as to be released therefrom by the action of a knife held in a carrier slidably engaged with the kite- 15 string and which is moved into operative position by the action of the wind that sustains the kite, further objects and advantages of the invention having relation to specific details of construction, all of which will be apparent from the following description.

In the drawings forming a portion of this specification, and in which like numerals of reference indicate similar parts in both views, Figure 1 is a perspective view showing a kite 25 equipped with the present invention. Fig. 2 is a longitudinal sectional view of the carrier or traveler which carries the knife that releases the parachute.

Referring now to the drawings, there is 30 shown a kite, including the crossed sticks 5, 6, and 7, upon which is fixed the body 8, at the lower end of which is attached the tail 9 by means of the cord 10 in the usual manner.

The bridle of the kite includes the six stays 35 11, each of which is attached at one end to one of the sticks of the kite-frame, and at its opposite end is attached to a plate 12, which is adapted to lie parallel with the face of the kite, and centrally of which is attached a ring 40 13 through the medium of a metal strip 14, the plate being of wood or of any other suitable light material of sufficient stiffness. To the ring 13 is attached the kite-string 15, by means of which the kite is flown.

45 The parachute that is employed is shown at 16 and may be of any specific construction to unfold when dropped, and it has a ring at its upper end, (shown at 17,) to which ring is attached a cord 18, which is taken upwardly 50 and through a ring or loop 19 at the point of crossing of the sticks of the kite-frame, then forwardly and through a second ring or loop

20 at the lower edge of the plate 12, and finally upwardly and is attached to the ring 13, the weight of the parachute holding the 55 string taut between the ring 13 and the lower edge of the plate, it being understood that the tension of the kite-string is sufficient to hold the ring 13 with the connection 14 taut. Thus if a knife be drawn across the cord 18 60 it may be readily cut and the parachute released and permitted to drop and unfold.

To cut the cord 18, a traveler is provided for the kite-string to run thereon, and consists of a frusto-conical body portion 20', of 65 paper, pasteboard, or other light material, at the minor end of which is a cylindrical extension 21, which carries an annular knife 22, the cutting edge of which is disposed away from the body portion of the traveler. Across 70 the major end of the body 20' are disposed wires 23, which carry a ring 24, while a second ring 25 is carried by other wires 26, disposed across the minor end of the body, and these two rings, which are centrally of the 75 body 20', have the kite-string passed therethrough, so that the carrier may slide freely along the kite-string.

In placing the carrier upon the kite-string the minor end thereof is disposed in the direction of the kite, so that the wind that sustains the kite may enter the major end of the carrier, and thus blow it along the kite-string and in the direction of the kite until the knife 22 is brought into contact with the 85 string 18 between the ring 13 and the lower edge of the plate 12, when the knife will cut the string and release the parachute in the manner above described.

It will be understood that in practice modifications of the specific construction shown may be made and that any suitable materials and proportions may be used for the various parts without departing from the spirit of the invention.

90 What is claimed is—

1. The combination with a kite and the string thereof, of a parachute having an attaching-string, means for holding the parachute-string at an angle to the kite-string, 100 and a traveler upon the kite-string and having a knife for engagement with the parachute-string to cut it.

2. The combination with a kite and the

string thereof, of a plate attached to the kite and with which the kite-string is connected, guides upon the plate and the kite, a parachute having an attaching - string passed through the guides and connected to lie at an angle to the kite-string, and a traveler disposed slidably upon the kite-string and having a knife for engagement with the string of the parachute to cut the string and release the parachute.

3. The combination with the kite, of a parachute attached to the kite by means arranged adjacent to the kite-string, and a traveler on the kite-string adapted to engage said attaching means and to effect the release of the parachute.

4. A wind - propelled traveler for kite-strings including a frusto-conical body por-

tion having guide-rings held centrally thereof to receive a kite-string, and an annular knife 20 at the minor end of the body portion.

5. The combination with a kite and the string thereof, of a parachute having an attaching-string secured to the kite, and a traveler movable upon the kite-string and having 25 a knife constructed and arranged for engagement with the string of the parachute to cut it and release the parachute.

In testimony that I claim the foregoing as my own I have hereto affixed my signature 30 in the presence of two witnesses.

SIDNEY W. FLETCHER.
